2 SHEETS—SHEET 2.

UNITED STATES PATENT OFFICE.

LEONIDAS G. THORNTON, OF WILLOWTON, WEST VIRGINIA.

WIRE-STRETCHER.

No. 910,029.

Specification of Letters Patent.

Patented Jan. 19, 1909.

Application filed August 4, 1908. Serial No. 448,578.

To all whom it may concern:

Be it known that I, LEONIDAS G. THORNTON, a citizen of the United States, residing at Willowton, in the county of Mercer and State of West Virginia, have invented certain new and useful Improvements in Wire-Stretchers; and I do hereby declare the following to be a full, clear, and exact description of the invention, such as will enable others skilled in the art to which it appertains to make and use the same.

This invention relates to wire stretchers, more particularly to devices of this character employed for stretching the strand members of wire fences, and has for one of its objects to simplify and improve the construction and increase the efficiency and utility of devices of this character.

With these and other objects in view the invention consists in a stock or frame constructed from a plurality of angle bars coupled at the ends with the confronting edges spaced apart to form guideways and with oppositely disposed ratchet teeth in the bars, a slidable member within the stock, a draw rod connected to the slidable member, and a lever swinging through the slidable member and provided with a pawl rib adapted to engage the ratchet teeth alternately.

The invention further consists in certain novel features of construction as hereafter shown and described and then specifically pointed out in the claims, and in the drawings illustrating the preferred embodiment of the invention.

Figure 1 is a side view of the improved device applied. Fig. 2 is a plan view of the improved device applied. Fig. 3 is a section on the line 3--3 of Fig. 2. Fig. 4 is a section on the line 4--4 of Fig. 2.

The improved device comprises a body or stock formed of four angle bars 10--11--12--13 coupled at the ends by U members 14--15 which are riveted or otherwise secured thereto at 16, the confronting edges of the angle bars spaced apart to form guideways extending longitudinally of the stock. One edge of the bar 12 is provided with ratchet teeth 17 while one edge of the bar 13 is provided with corresponding teeth 18.

Slidably disposed within the stock are two blocks 19--20, the blocks extending respectively between the angle bars 10--11 and 12--13 and coupled outside the bars by plates 21--22 extending at the edges over the bars, the four parts 19--20--21--22 con-

stituting a sliding member within the stock.

Connected to the U shaped member 15 is a hook 23, and connected to the block 19 is a rod 24 extending loosely through the U shaped member 14 and terminating in a hook 25.

Extending through the plates 21--22 is a pin 26 and swinging upon this pin is a lever 27 having a handle 28 at its free end and with one edge bent at right angles to form a pawl 29 for alternately engaging the teeth 17--18.

All the parts are of metal, preferably of steel, and of sufficient strength to withstand the severe strains to which they will be subjected.

In using the improved device, the hook 23 is coupled by a chain 30 to a stationary object, or to a post especially erected for the purpose, and the slidable lever carrying member moved to the opposite end of the stock with the rod 24 extending beyond the stock. The hook 25 is then coupled to the wire to be stretched by a suitable grip device indicated at 31. The lever 27 is then engaged alternately with the teeth 17--18 by its pawl rib 29 and moved back and forth upon its pin 26, and thus move the slidable member step by step to the hook end of the stock. The lever 27 is considerably thinner than the spaces between the bars 10--12 and between the bars 11--13, so that when released from the teeth, the lever can be moved upon the pin 26 to clear the pawl rib 29 from engagement with the teeth, and thus enable the slidable member together with the lever and rod 24 to be moved bodily in the stock. By this means when the wire has been stretched as far as the length of the stock will permit, the partly stretched wire is secured and the slidable member adjusted to a new position and the operation repeated, and so on as often as necessary.

The improved device may be inexpensively manufactured, is very strong and durable, as the members are disposed to secure the greatest resistance with the least weight of material, and can be manufactured from stock already on the market with very little change in the structure of the parts.

What is claimed, is:-

1. A wire stretcher comprising a stock formed of a plurality of spaced angle bars arranged in pairs and coupled at their ends and forming guideways, the opposite edges of one pair of said bars having ratchet teeth,

a head member within said stock and slidably engaging the bars between the end couplings, a pull rod connected to said head and extending through one of said end couplings 5 and guided thereby, a lever swingingly connected to said head member and with one edge directed laterally therefrom and engaging said ratchet teeth.

2. A wire stretcher comprising a stock 10 formed of angle bars coupled at the ends and spaced apart to form guideways, two opposite edges of the bars having ratchet teeth, a head member within the stock and formed of two blocks spaced apart with projections 15 extending between two opposite pairs of the angle bars, plates connected to the projecting portions of the blocks and extending over the outer faces of the bars, a pin extending through said plates, a lever swinging upon 20 said pin and provided with a pawl rib adapted to alternately engage with said ratchet teeth, and a pull rod connected to one of said blocks.

3. A wire stretcher comprising a stock

formed of a plurality of longitudinally disposed angle bars spaced apart to form guideways, two of the bars having ratchet teeth 25 in their edges, U plates at the ends of the bars and to which they are coupled, a head member within the stock and formed of two blocks spaced apart with projections extending 30 between two opposite pairs of the angle bars, plates connected to the projecting portions of the blocks and extending over the outer faces of the bars, a pin extending through said plates, a lever swinging upon 35 said pin and provided with a pawl rib adapted to alternately engage with said ratchet teeth, and a pull rod connected to one of said blocks and extending through 40 one of said U plates.

In testimony whereof, I affix my signature, in presence of two witnesses.

LEONIDAS G. THORNTON.
